UNITED STATES PATENT OFFICE.

CHARLES SINCLAIR DRUMMOND, OF LONDON, ENGLAND.

FURNACE.

964,502.

Specification of Letters Patent. Patented July 19, 1910.

Application filed June 13, 1908. Serial No. 438,423.

To all whom it may concern:

Be it known that I, CHARLES SINCLAIR DRUMMOND, subject of the King of Great Britain, residing at No. 23 St. Mary Axe, 5 in the city of London, England, have invented new and useful Improvements in Furnaces, of which the following is a specification.

This invention relates to improvements in 10 the construction of furnaces for the combustion of solid fuel on a closed hearth without a fire grate.

On the accompanying drawing are shown 15 as representative examples some forms of a furnace constructed according to the above described invention.

In this drawing:—Figure 1 is a part plan of a circular furnace. Fig. 2 is a plan of a 20 rectangular furnace. Fig. 3 is a vertical section corresponding to Fig. 2, and:—Fig. 4 shows a modification of construction.

Referring to Figs. 1 and 3, *a*—*a* are a plurality of similar moldings or castings which, when assembled, compose a complete 25 circular wall which surrounds a space for the reception of the fuel, the floor being a closed hearth *b* formed of refractory material.

Around the outside of the wall a passage 30 *c* is provided, the boundary on the furnace side consisting of the said wall, the upper boundary being a horizontal flange *a*¹ of the elements *a* and the outer boundary of the passage consisting of the lower portion *d* of 35 the side of the furnace.

The passage *c* is in communication with the external atmosphere through the opening *e* which, by the branch *f*, leads beneath the foot *g* of the boiler to which heat is 40 being supplied by the furnace.

From the upper side of the passage *c* the air flows to the furnace through a series of tubular downward extending channels *h* formed in locally thickened portions of 45 the wall of the elements *a*, the thickened portions protruding into the furnace and presenting an augmented surface for the reception of heat which is conducted through the metal and heats the incoming

50 air. The tubular channels extend downward to a comparatively short distance from the furnace-hearth and thus the air is supplied well beneath the burning fuel through which it passes upward and

emerges in the condition of burnt gases 55 through the flue-passage *i*.

In furnaces which are wide or of large diameter some of the air admission channels *h* may be prolonged so as to conduct some of the air toward the center of the bed of 60 fuel as by laying an inverted piece, of channel section, on the hearth of the furnace as indicated at *h*¹ in Fig. 1.

To unite together in a secure and fluid-tight manner the abutting surfaces of the 65 elements *a*, grooves *j* of dove-tail section are provided into which a prism of double dove-tail section can be dropped and the remainder of the grooves filled with fire-clay. The joint between the flange *a*¹ and the furnace 70 plate is also rendered stanch by means of fire-clay or asbestos as indicated at *k*.

Fig. 4 shows in section a modified form of construction in which both the inner and the outer walls of the passage *c*, and also 75 the crown thereof, are cast integrally, tubular channels *m* being formed at intervals within the thickness of the wall next the fire. A ring of such a section or a plurality of united elements of such a section are 80 supported on a ring-base *n* so dimensioned that the orifices at the lower extremity of the tubular channels *m* overhang the base *n* and provide an annular passage around the inside of the furnace beneath the foot of 85 the wall for the more freely extended distribution of the entering air to the burning fuel.

The boiler rests on the integral or built-up ring which composes the furnace, an internal flange *o*, extending upward, serves to center the furnace relatively to the boiler and protect the heads of the rivets from the heat of the fire the space between the flange *o* and the furnace-plate *d* being filled with 95 asbestos or fire-clay.

With this last described construction the examination and repair of the interior of the furnace will be facilitated. For by lifting the boiler the short distance of the 100 height of the flange *o*, the furnace ring can be withdrawn laterally apart from the boiler.

I claim:

1. In a furnace, a closed hearth, a wall 105 surrounding the space for the reception of fuel on said hearth, said wall being surrounded by a passage in communication with

the atmosphere and having channels formed therein leading from the upper portion of said passage to the interior of the furnace and terminating within the fuel space 5 slightly above said hearth.

2. In a furnace, a closed hearth, a wall surrounding the space for the reception of fuel on said hearth, said wall being surrounded by a passage in communication with 10 the atmosphere and having channels formed therein leading from the upper portion of said passage to the interior of the furnace and terminating within the fuel space slightly above said hearth, the walls of said 15 channels protruding into the interior of the furnace.

3. In a furnace, a closed hearth, a wall surrounding the space for the reception of fuel on said hearth, said wall being surrounded by a passage in communication with 20 a conduit leading from the atmosphere thereto and having channels formed therein leading from the upper portion of said passage to the interior of the furnace and terminating within the fuel space slightly 25 above said hearth.

4. An element of a furnace, comprising a wall, an upper flange on the outside of said wall, said wall having tubular channels leading from beneath the said flange downward 30 and forming projections on the fire-exposed

side of said wall, said channels opening on the inner side of said wall adjacent its lower end.

5. An element of a furnace, comprising 35 a wall, an upper flange on the outside of said wall, said wall having tubular channels leading from beneath the said flange downward and forming projections on the fire-exposed side of said wall said channels 40 opening on the inner side of said wall adjacent its lower end, and the ends of said element being formed with undercut grooves.

6. In a furnace, a closed hearth, a plurality of elements assembled as a complete wall 45 around the space for the reception of fuel on said hearth, an upper outwardly directed flange on each of said elements, locally thickened portions on the fire-exposed side of said elements having tubular channels leading from beneath said flange downward, and an outer wall so surrounding said assembled elements and abutting against said flange as to inclose an annular space in communication with the atmosphere. 50

In testimony whereof I have signed my name to this specification in the presence of two subscribing witnesses.

CHARLES SINCLAIR DRUMMOND.
